UNITED STATES PATENT OFFICE.

MICHAEL F. DAVORAN, OF CINCINNATI, OHIO, ASSIGNOR TO THE CRANE & BREED MANUFACTURING COMPANY, OF CINCINNATI, OHIO, A CORPORATION OF OHIO.

BURIAL CASKET.

Application filed February 14, 1927. Serial No. 168,153.

It is the object of my invention to provide a burial casket so constructed that it may be arranged in such manner as to depart from the funeral effect incident to burial caskets as heretofore made.

To accomplish this I construct the casket in novel manner and provide novel means whereby the casket is arranged in imitation of a day bed upon which the body is capable of being arranged in the attitude of sleep.

It is the object of my invention, further, to provide the side walls of the casket with movable upper sections for exposure of the body receiving cavity in the casket; and, further, to so drape the casket as to hide the casket portions thereof, and so arrange both sides of the casket as to produce the effect of a bed on which the body reposes.

The invention will be further readily understood from the following description and claims, and from the drawings, in which latter:

Fig. 1 is a side elevation of my improved casket in closed relation, the lid being partly broken away.

Fig. 2 is a perspective view of the same in open relation, the lid being removed.

Fig. 3 is a plan view of the framing of the casket, with the movable upper side sections in lowered relation.

Fig. 4 is a vertical cross-section of my improved device, shown in open relation, with the lid removed, and taken in the plane of the section line 4—4 of Fig. 2; and,

Fig. 5 is a detail view in side elevation of the fastening means for the movable side sections.

The body of the casket comprises side walls 11, which at both sides of the casket have gaps 12 arranged therein, arranged to be filled by movable side wall sections 13, movable with relation to the rigid portions of the side walls so as to be placed in sidewise unobstructing relation at both sides of the body receiving cavity 14 in the casket. The casket is also provided with end walls 15.

The gaps in the respective rigid side walls are preferably shorter than the full length of the side walls, the upper parts of the side walls having end portions 16, whose inner ends preferably slope downwardly and inwardly, as shown at 17. The movable upper side wall sections have complementary ends 18. These movable sections are shown as hinged by hinges 19 to the fixed portions of the side

walls, and as arranged to be folded downwardly for being droopingly suspended at both sides of the casket, as shown for instance in Fig. 4.

The casket has therein a support 21, on which a cushion support or mattress 22 is supported.

The fixed portions of the side walls are provided with usual handles 23, below the gaps in said side walls, and the end walls may be provided with end handles 24. The side handles may be connected by a long bar at each side of the casket. The inside faces of the walls may be provided with lining 25 of usual character.

Drapery 31 is arranged to be received across the cushion support, through the gaps at both sides of the casket, and draping at the outside of the movable sections of the side walls and the handles, as well as along the sloping ends of the gaps, avoiding sharp or protruding corners under the drapery, the drapery also preferably extending across the tops of the fixed end portions of the side walls and the end walls, being draped over said end walls and the handles thereon and preferably entirely hiding the casket.

The fixed end portions 16 of the side walls and the upper portions of the end walls form end spaces at the respective ends of the casket over which the drapery is preferably located, and these end spaces are arranged to receive pillows 32, 33, which are adjustable endwise of the casket in said end spaces for adjusting the distance between them for accommodating bodies of different lengths in the casket. These pillows form rests for the head and feet respectively of the body. The pillows are provided with side tabs 34, 35, at each end of the pillows, which tabs are draped over the respective ends of the side walls of the casket at both sides thereof and aid in forming a pleasing effect.

In my improved device the casket, when arranged for receiving the body, is changed into a form in imitation of a day bed, on which the body is laid in imitation of a posture of sleep, the movable sections of the side walls of the casket being placed in unobstructing relation, so as to simulate a flat bed at both sides of the casket, and for exposing both sides of the draped body in the casket, giving the body an elevated appearance as if reposing on top of a bed, in contradistinction to the funeral effect produced in cas-

quets as heretofore constructed in which the body was sunk into the casket.

When closing the casket the overhanging tabs 34, 35, are arranged lengthwise at the inner side of the side walls of the casket at the respective ends of the latter, and the drapery is folded inside the casket alongside of and at the head and foot of the body. The movable sections of the side walls are raised to fill the gaps in said side walls. Suitable fastening means are preferably provided for holding said movable sections in place, for instance by providing flat hooks 36 and complemental eyes 37 respectively on the inner faces of the ends of said movable sections and the complemental end walls of the gaps, preferably under the inner linings thereof.

The lid 38 is preferably removable from the body of the casket, and is removed during viewing of the body in the casket. The lid is arranged to be fastened in place by usual fastening means, when attached to the body of the casket, for locking the lid to the body of the casket.

The inner face of the lid is provided with usual lining 39. The lid has an upwardly extending dome 40 for providing ample cavity 41 under the lid for accommodation of the body in the casket. The cavity 41 is of greater height than the height of the movable side wall section 13, as shown in Fig. 1.

Having thus fully described my invention,

what I claim as new, and desire to secure by Letters Patent, is:

A burial casket comprising a body portion having rigid end walls of full height and side walls, each of said side walls having rigid end portions of full height and a rigid median portion of partial height, said rigid median portion of partial height extending throughout the major portion of said side wall, the inner ends of said rigid end portions of full height of each of said side walls having sloping inner ends in the plane of said rigid end portions and sloping inwardly and downwardly toward said rigid median portion of partial height, a body-support of substantially the height of said rigid median portions of partial height, said body-support located between said walls, each of said side walls thus formed provided with a gap above said rigid median portion thereof of partial height between said sloping inner ends, movable sections for both said side walls, each of said movable sections provided with sloping outer ends complemental to said sloping inner ends, a removable lid provided with an upwardly extending dome above said body-support, the inner space of said dome being higher than the height of said movable sections, and releasable securing means between said lid and said body-portion.

In testimony whereof, I have hereunto signed my name.

MICHAEL F. DAVORAN.
